UNITED STATES PATENT OFFICE.

WALTER F. KASPER, OF FAIRMONT, MINNESOTA, ASSIGNOR TO FAIRMONT GAS ENGINE & RAILWAY MOTOR CAR COMPANY, OF FAIRMONT, MINNESOTA, A CORPORATION OF MINNESOTA.

THROTTLE VALVE.

1,423,858.

Specification of Letters Patent. Patented July 25, 1922.

Application filed March 12, 1920. Serial No. 365,344.

To all whom it may concern:

Be it known that I, WALTER F. KASPER, a citizen of the United States, resident of Fairmont, county of Martin, State of Minnesota, have invented certain new and useful Improvements in Throttle Valves, of which the following is a specification.

My invention relates to throttle valves for internal combustion engines of the two cycle type in which a combustible charge is admitted and compressed in the crank chamber of the engine and thereafter transferred, through a by-pass, and port to the combustion cylinder. In this type of engine it is difficult to secure uniform distribution of the combustible gas when it enters the combustion cylinder with the result that missing takes place, especially when the engine is throttled down for lower speeds and lighter loads.

The object of the invention is, therefore, to provide means in connection with a throttle valve for securing more uniform distribution in the combustion cylinder of the entering combustible for all loads and speeds of the engine, and particularly to so direct the gas stream to procure a richer mixture at, or near the spark plug origination point when the engine is throttled down, thus insuring positive ignition of lean charges when idling the engine at a low speed and preventing misfiring.

My invention consists in certain constructions and combinations, all as hereinafter described and particularly pointed out in the claims, taken in connection with the accompanying drawings, in which—

Figure 1 is a longitudinal vertical section of a two cycle engine having my invention applied thereto,

Figure 2 is a transverse section of the engine on the line 2—2 of Figure 1,

Figure 3 is a perspective view of the throttle valve constructed according to my invention,

Figure 4 is a detail section illustrating the method of throttling.

In the drawings, 5 is the crank chamber into which is drawn a combustible mixture of gas through a check valve 6 from any suitable source, such as a carburetor (not shown). 7 is the crank shaft, 8 the connecting rod to the piston 10 operating in the cylinder 11 and having a baffle plate member

12, projecting a considerable distance into the combustion chamber 13. The spark plug 14 for the ignition of the combustible charge, is located in the center of the cylinder head 15 towards which the baffle member 12 projects. The combustible gas enters the combustion chamber 13 under pressure through a by-pass 16 and an intake port 17, when the piston 10 is at the inner end of its stroke, as shown in Figure 1, and the burnt gases escape through the exhaust port 18.

As the intake port must be of considerable length, as shown in Figure 2, to secure the proper volumetric efficiency at high speed and full load of the engine, and as therefore at light load or when idling the engine the valve is adjusted to admit a very small portion of gas, the gas stream admitted by an ordinary throttle valve becomes extremely long and thin and being inducted in this form into the combustion cylinder, becomes too readily diffused and mixed with the exhaust gases, thus making the mixture difficult of ignition.

To overcome this defect, I mount a rotary throttle valve 20 in a housing or seat 21 in close proximity to the intake port 17, the valve having gas tight seats 22 and 23 in heads 24 and 25 and annular seats 26 and 27 at its ends. This method of induction prevents the mixing or diffusion of the combustible gas with the exhaust gases and localizes the gases around the spark plug where it will be readily ignited. The advantage of this valve construction lies generally in the fact that as the charge is throttled, the incoming gas stream is gradually narrowed down from both ends toward the center of the valve and a full square gas stream, passing through the exhaust gases without materially diffusing, is directed to the cylinder head and, accumulating around the spark plug, displaces the exhaust gases and insures constant ignition and economy.

The valve has a stem 28 with an opening lever 29 and a long segmental valve port 30 is recessed between the circular seats 26 and 27. Centrally in this port I provide stepped recesses 31 and 32 of shorter and deeper dimensions, the said recesses being cut in the side of the port 30 which controls the port 17.

It will be understood that any number of steps may be provided and other equivalent

construction of the valve substituted without departing from the scope or principle of the invention.

The central recess 32 is quite short and deep and when the valve is adjusted to throttle the charge for light load or idling of the engine, as illustrated in Figure 4, the port 30 and recess 31 are closed and the small amount of gas needed can enter only through 10 the centrally located recess 32 and will be inducted into the cylinder in a full stream or pencil directed against the head 15 and spark plug 14, the pencil-like stream being guided in this direction by the baffle member 15 ber 12.

I claim as my invention:

1. A throttle valve for a two-cycle internal combustion engine comprising a cylindrical valve body having a segmental longitudinal port and stepped peripheral recesses in the walls of said port, said recesses differing in length and depth, the shortest and deepest recess being centrally arranged with respect to said port.

2. A throttle valve for a two-cycle internal combustion engine comprising a cylindrical valve body having a segmental longitudinal port, one side of said port being substantially parallel to the valve body 30 and the opposite side of said port being recessed progressively deeper towards its center from both ends of said port.

3. A throttle valve for a two-cycle engine comprising a rocking cylindrical valve body 35 having a longitudinal segmental port opening and a recess stepped from both ends of the port opening for longitudinally con-

tracting or extending the length of said port opening when said valve is rocked.

4. A throttle for a two-cycle engine comprising 40 a rocking cylindrical valve body having a longitudinal segmental port opening therein, a wall of said port opening having a series of recesses progressively shorter and stepped deeper from the ends toward 45 the center of said port opening.

5. A throttle valve for a two cycle internal combustion engine comprising a rotatable cylindrical valve having a segmental port along one side, said port having an 50 arcuate bottom wall, and a shorter port formed in one edge of the segmental port and having an arcuate bottom wall merging into the bottom wall of the first port at a point intermediate its side edges. 55

6. A throttle valve for a two cycle internal combustion engine, comprising a rotatable cylindrical valve having a segmental port along one side, said port having an arcuate bottom wall, and a plurality of ports 60 progressively decreasing in length and increasing in depth from the opposite ends of the segmental port and formed in one side edge thereof, the bottom walls of the second ports, being arcuate and merging into the 65 bottom wall of the first port in progressively spaced order from said side edge thereof.

In witness whereof, I have hereunto set my hand this 8th day of March 1920.

WALTER F. KASPER.
